UNITED STATES PATENT OFFICE.

GEORGE W. LARUE, OF NEW YORK, N. Y.

DESIGN FOR A SEWING-MACHINE FRAME.

SPECIFICATION forming part of Design No. 24,550, dated August 13, 1895.

Application filed February 4, 1895. Serial No. 537,302. Term of patent 14 years.

To all whom it may concern:

Be it known that I, GEORGE W. LARUE, of New York, in the county of New York and State of New York, have invented a new Design for Sewing-Machine Frames; and I do hereby declare the following, when taken in connection with the accompanying drawings and the letters of reference marked thereon, to be a full, clear, and exact description of the same, and which said drawings constitute part of this specification, and represent, in—

Figure 1, a view in side elevation; Fig. 2, an edge view.

This invention relates to a design for sewing-machine frames, and the design consists in the configuration as hereinafter described, and shown in the accompanying illustrations.

As herein shown, my newly-designed sewing-machine frame has two corresponding outwardly-curved feet A A, located at the opposite ends of a flat table B, from the rear end

of which rises a ribbed arm C, which curves forward and terminates in a head D, having legs D' D' located over the work-table E, which is supported upon a vertical arm F, rising from the forward edge of the table. From the front face of the arm C, near the lower end thereof, is an offset G, and from the front face of the arm and on the curved upper portion thereof is an offset H, and on the vertical arm F are two offsets I.

I claim—

The design for sewing-machine frames as described and shown in the accompanying illustrations.

In testimony whereof I have signed this specification in the presence of two subscribing witnesses.

GEORGE W. LARUE.

Witnesses:

FRED C. EARLE,
LILLIAN D. KELSEY.
